UNITED STATES PATENT OFFICE.

MERRITT B. BRADT, OF PENNINGTON, NEW JERSEY, ASSIGNOR TO PEERLESS INSULATED WIRE & CABLE COMPANY, OF NEW YORK, N. Y., A CORPORATION OF DELAWARE.

WIRE-COVERING MACHINE.

1,411,233.

Specification of Letters Patent. Patented Mar. 28, 1922.

Application filed March 9, 1920. Serial No. 364,493.

To all whom it may concern:

Be it known that I, MERRITT B. BRADT, a citizen of the United States, residing at Pennington, in the county of Mercer and State of New Jersey, have invented certain new and useful Improvements in Wire-Covering Machines, of which the following is a specification, reference being had therein to the accompanying drawings, which form 10 a part thereof.

My invention relates to wire covering machines, and more particularly to a machine for providing an electroconductive wire with a cover of cotton sliver or other absorptive, fibrous material, and an outer tubular braid.

Heretofore, in the manufacture of braid covered insulated wire, it has been the practice to first cover the wire core with spirally wound cotton sliver or other similar absorptive, fibrous material, and apply a binding cord or strand thereto, and winding the wire so covered upon a reel. Thereafter, this reel was mounted in an ordinary braiding machine in which the outer braid was applied thereto, the binding cord or strand preventing the unwinding of the sliver, and its expansion while the braid was being so applied. The product of the two machines 25 was a covered wire in which the braid was separated from the sliver by the interposed binding cord or strand, thus causing a loss of homogeneity in the completed wire even after it had been saturated or impregnated 30 with the asphaltum or other composition.

By means of a machine made in accordance with my invention, I am not only enabled to produce a wire, the covering for which consists of a strip or strips of loosely matted cotton sliver, or other similar absorptive, fibrous material, held in place by an outer braid, without the presence of an interposed binding cord or strand, but apply this covering in its entirety, by means of 40 a single machine, and by means of a continuous operation. In this manner I avoid that waste represented by the value of the binding cord or strand, and produce a superior product, inasmuch as the strands of 45 the braid will be imbedded directly in the spirally wound fibrous strips, and the external fibers of said strips will be enmeshed or entangled in the meshes of said braid. Furthermore, the use of a machine made in accordance with my invention enables me to 50

dispense with the use of the adhesive ordinarily applied to the conductive wire, since the capacity of the machine is proportioned to that of the braiding mechanism forming a part thereof, thus reducing likelihood of the slippage of the fibrous strips. 60

Ordinarily a machine made in accordance with my invention is designed to apply the covering material to larger wires in which two or more plies of the sliver strip are 65 applied to the conductor wire.

The invention consists primarily in a wire covering machine embodying therein a rotatable platform having an opening axially thereof and adapted to receive a container 70 for a coil of cotton sliver or other absorptive fibrous material, a compacting die above, and in axial alignment with, said platform, means simultaneously rotating said platform and said die, a braiding 75 mechanism above said die, and operative connections between said platform and said braiding mechanism, whereby said braiding mechanism will be actuated at a relatively higher speed than said platform; and in such 80 other novel features of construction and combination of parts as are hereinafter set forth and described, and more particularly pointed out in the claims hereto appended. 85

Referring to the drawings,

Fig. 1 is a front elevation of a machine embodying my invention, parts thereof being shown in vertical section; and

Fig. 2 is a plan view thereof.

Like letters refer to like parts in both 90 of said views.

In the embodiment of my invention shown in the drawings, I have indicated at *a* the main frame of the machine having rotatably mounted adjacent the bottom thereof, a 95 circular platform *b* adapted to receive one or more containers *c* for the coils of cotton sliver or other similar material. The platform *b* is provided centrally thereof with an opening *b'* through which a conductor wire *d* passes and is fed upwardly to a feed drum *e*, surmounting the entire machine. The platform *b* at the edge thereof has an ordinary spur gear *b*² through which rotary movement is imparted thereto. 100

The platform *b* has a superstructure *f* by means of which a compacting die *f'* is supported with the axis thereof in vertical alignment with the opening *b'* in said platform. In this manner said die and said 110

platform are rotated simultaneously in the same direction, so that as the sliver indicated at *g* is spirally wound about the wire *d*, it will be compressed to size and compacted in a manner to matte the fibers of the sliver or other material, and bring the covered wire to substantially the same diameter throughout.

The frame *a* above the compacting die *f'* 10 supports a braiding mechanism *h* of the usual and well known construction, including tensioning devices *h'*, an actuating gear train *h²*, and a slotted plate *h³*, for imparting the desired direction of travel to the 15 various spindles supporting the spools containing the cords or strands from which the braid is formed. The operation of this braiding mechanism is old and well known in this art, and description of further details thereof is therefore not essential.

The gear train *h²* has power transmitted thereto through the gear *h⁴*, the shaft *h⁵* of which has a worm *i* thereon meshing with the worm wheel *i'*, the shaft of which is 25 connected by a suitable gear train *j—j'* with the feed drum *e*. The shaft *h⁵* also has a hand crank *i²* by means of which the machine may be hand operated when setting up for a run thereof.

Since the strips of sliver or other material will ordinarily be at least an inch in breadth, it is apparent that to properly synchronize the various functions in a machine, it is essential that the platform *b* shall have but 35 one rotation or cycle thereof during that interval in which the braiding mechanism shall have covered a length of wire corresponding with the breadth of said sliver, and that the functions of the platform and the braiding mechanism shall be so synchronized as to secure a uniform finish of the product.

To secure the desired result, I provide a gear connection between the gear *b²* upon 45 the edge of the platform *b* and the gear *h⁴* transmitting power to the braiding spindles, the ratio of this gearing being such as to secure the desired relative speeds of the platform and said braiding mechanism. 50 This gearing consists of a shaft *k* having at one end thereof a gear *k'* meshing with the gear *h⁴*, and carrying a gear *k²* meshing with the gear *b²*. If desired, power may be applied to the sliver winding mechanism 55 and also to the braiding mechanism through the pulley *k²* upon said shaft *k*.

One or more containers *c* may be mounted upon the platform *b* according to the number of plies of the sliver which are to 60 be applied to the wire *d*. Ordinarily at least two such plies would be applied.

The operation of the herein described device is substantially as follows:—

When starting a machine, the end of the 65 wire *d* will be secured to a rope or cord

which will be fed through the opening *b'* of the platform *b*, through the compacting die *f'*, and about the feed drum *e*.

In starting the machine, the sliver winding mechanism and the braiding mechanism 70 may be actuated through the hand crank *i²* until a sufficient length of wire has been covered with sliver and had the braid applied thereto, to ensure proper conditions during a continuous run of the machine. 75 This actuation of the shaft *i* by the hand crank *i²* will ensure the actuation of both the braiding mechanism and the sliver winding mechanism at the proper relative speeds, through the gears *h⁴* and *b* and the gears 80 *k'*—*k²* upon the shaft *k*.

When this condition has been established, power is applied to said shaft *k* and thereafter the machine will run automatically, the spiral trend of the sliver upon the wire 85 *d* being controlled by the rate of lineal traverse of said wire under the control of the drum *e*, which speed will be determined and controlled by the capacity of the braiding mechanism.

As the wire with the sliver thereon passes through the die *f'*, it will be tightly wound thereon and compacted so as to matte the fibers of the sliver, and when two or more plies of sliver are used, secure a proper 95 bond between the succeeding plies, which should be so set with relation to the wire that the abutting or lapping edges of one ply will lap those of the other, thus securing continuity in the matted body thus applied to the wire.

After leaving the die *f'* there will be a slight tendency of the compacted sliver to expand and the outer fibers thereof to spring outwardly, so that these fibers will be caught 105 in the meshes of the braid and entangled or enmeshed therein so as to ensure a firm bond of the strands of said braid to the body portion of the covering material. At the same time the tensioning devices will hold the various strands of the cord forming the braid, sufficiently taut to imbed them well within the surface of the sliver, so that after the application of the asphaltum or other composition to the covered wire, and during the 115 final finishing operations of sizing and ironing, portions of said sliver will be forced over the edges of the braid and thus more firmly bond the braid to the body of the covering.

It is not my intention to limit the invention to the precise details of construction shown in the accompanying drawings, it being apparent that such may be varied without departing from the spirit and scope of 125 the invention.

Having described the invention, what I claim as new and desire to have protected by Letters Patent, is:—

1. A wire covering machine embodying 130

therein a rotatable platform having an opening axially thereof and adapted to receive a container for a coil of cotton sliver or other absorptive fibrous material, a compacting die above, and in axial alinement with, said platform, means simultaneously rotating said platform and said die, a braiding mechanism above said die, operative connections between said platform and said braiding mechanism, whereby said braiding mechanism will be actuated at a relatively higher speed than said platform, and means for imparting continuous traverse to a wire with relation to said platform, said die and said braiding mechanism.

2. A wire covering machine embodying therein a rotatable platform having an opening axially thereof and adapted to receive a container for a coil of cotton sliver or other absorptive fibrous material, a compacting die above, and in axial alinement with, said platform, means simultaneously rotating said platform and said die, a braiding mechanism above said die, a gear train connecting said platform and said braiding mechanism, the ratio of said gearing being such that said braiding mechanism will be actuated at a relatively higher speed than said platform, and means for imparting continuous traverse to a wire with relation to said platform, said die and said braiding mechanism.

3. A wire covering machine embodying therein a rotatable platform having an opening axially thereof and adapted to receive a container for a coil of cotton sliver or other absorptive fibrous material, a compacting die above, and in axial alinement with, said platform, means simultaneously rotating

said platform and said die, a braiding mechanism above said die, a gear train connecting said platform and said braiding mechanism, the ratio of said gearing being such that said braiding mechanism will be actuated at a relatively higher speed than said platform, means for imparting continuous traverse to a wire with relation to said platform, said die and said braiding mechanism, and a speed reducing mechanism connecting said gear train with said last named means.

4. A wire covering machine embodying therein a rotatable platform having an opening axially thereof and adapted to receive a container for a coil of cotton sliver or other absorptive fibrous material, a compacting die above, and in axial alinement with, said platform, means simultaneously rotating said platform and said die, a braiding mechanism above said die, a gear train connecting said platform and said braiding mechanism, the ratio of said gearing being such that said braiding mechanism will be actuated at a relatively higher speed than said platform, means for imparting continuous traverse to a wire with relation to said platform, said die and said braiding mechanism, a speed reducing mechanism connecting said gear train with said last named means, and means whereby said gear train may be manually actuated.

In witness whereof I have hereunto affixed my signature, in the presence of two subscribing witnesses, this 27 day of Feb. 1920.

MERRITT B. BRADT.
